T. F. LITTLE, SR

WINDOWED UMBRELLA

Filed August 22, 1924

INVENTOR
Thomas F. Little, Sr.
BY *John H. Hockley*
ATTORNEY

UNITED STATES PATENT OFFICE.

THOMAS FRANCIS LITTLE, SR., OF LAUREL HILL, NEW YORK.

WINDOWED UMBRELLA.

Application filed August 22, 1924. Serial No. 733,405.

To all whom it may concern:

Be it known that I, THOMAS F. LITTLE, Sr., citizen of the United States, residing at Laurel Hill, Long Island, in the county of Queens and State of New York, have invented certain new and useful Improvements in Windowed Umbrellas, of which the following is a specification.

This invention relates generally to umbrellas, having more particular reference to the provision of a transparent element in the umbrella cover which will permit of the user of the umbrella seeing in front of him while holding the umbrella tilted before him.

The invention has for an object the provision of a novel and improved umbrella of this type.

For further comprehension of the invention, and of the objects and advantages thereof, reference will be had to the following description and accompanying drawing, and to the appended claim in which the various novel features of the invention are more particularly set forth.

Fig. 1 of the drawing is a side view of an umbrella having my invention applied thereto.

Fig. 2 is a plan view.

Fig. 3 is a fragmentary sectional view taken along the line 3—3 of Fig. 2.

Fig. 4 is a fragmentary sectional view taken on the line 4—4 of Fig. 2.

Fig. 5 is a fragmentary plan view showing a modification.

In the drawing the reference numeral 10 indicates the usual shaft of an umbrella, certain of the ribs being indicated, and numbered 11. The cover of the umbrella may be of silk, cotton or any suitable material, and is shown at 12, this cover being attached to the ribs of the umbrella in the usual manner. According to my invention I provide, at suitable points in the said cover, preferably adjacent the edge thereof, one or more sight apertures for the convenience of the user of the umbrella.

To provide the sight aperture the outer portion of one of the panels of the cover may be detachably connected at its sides to the adjacent ribs. It will be understood that by a

panel of the cover I mean the section thereof between a pair of ribs. This outer detachable panel portion is indicated at 12', and it may be of such dimension, radially considered, as may be desirable. The edges of the outer portions of the adjacent panels are attached to the ribs in any suitable manner as by stitching passed through said outer portions and through apertures formed in the ribs and spaced therealong. The outer panel portion 12' is provided with a number of hooks 15 spaced along the edges thereof, and these hooks are engaged with eyes 16 spaced along the adjacent ribs 11 to retain the said outer portion in position when it is not desired to employ the sight aperture.

When the sight aperture is to be employed this outer element 12' is turned backward under the cover of the umbrella as shown in Fig. 3 and may be secured in such turned back position by passing the outer pair of the hooks 15 through eyes 17 attached to the inner face of the cover 12. A transparent section 18, which may be of sheet celluloid for any suitable transparent material having sufficient flexibility, is then attached to the two adjacent ribs in place of the turned back element, this section having a surrounding cloth border or frame 19 in which it is permanently mounted, this frame or border having attached to opposite sides thereof hooks 20 that are engaged with the eyes 16 on the ribs 11. When the transparent section is not in use it may be readily rolled up and carried in the pocket of the user. This section 18 might be subdivided into a number of individual panes if desired.

In Fig. 5, I have shown a different embodiment of my invention in which one or more smaller transparent panels 22 are inserted into the cover of the umbrella, and are here shown as provided with covering flaps 23 that may be turned back when the transparent sections are being utilized, suitable snap fastener elements 24 being provided to retain the flaps in the selected position.

Having thus described my invention, what I claim as new and desire to protect by Letters Patent of the United States is as follows:—

In an umbrella, a movable cover section part having substantially the shape of a truncated cone, means for normally holding said movable section in place between two adjacent ribs allowing a folding back of said movable section to any desired extent, means for locking said movable section in its fold-

ed back position, said first named means adapted to allow the securing of a transparent sheet to replace the folded back part of 10 said movable section to allow a clear view.

In testimony whereof I have affixed my signature.

THOMAS FRANCIS LITTLE, Sr.
